CLAIM

The ornamental design for a bed as shown and described.

DESCRIPTION

FIG. 1 is a perspective view of the bed;

FIG. 2 is a front elevational view of the bed;

FIG. 3 is a rear elevational view of the bed;

FIG. 4 is a left side elevational view of the bed; the right side of which is a mirror image;

FIG. 5 is a top plan view of the bed; and,

FIG. 6 is a bottom plan view of the bed.

The broken line portions of the drawings are included to show portions of the bed that form no part of the claimed design.
